UNITED STATES PATENT OFFICE.

HENRY KURK, OF NEW ALBIN, IOWA.

TRACTOR-WHEEL.

1,316,453.

Specification of Letters Patent. Patented Sept. 16, 1919.

Application filed December 6, 1918. Serial No. 265,577.

To all whom it may concern:

Be it known that I, HENRY KURK, a citizen of the United States, residing at New Albin, in the county of Allamakee and State 5 of Iowa, have invented new and useful Improvements in Tractor-Wheels, of which the following is a specification.

This invention relates to improvements in tractor wheels of that type wherein mud- 10 hooks are arranged for connection with the wheel and adapted to be projected into an operative position or withdrawn into an inoperative position at the will of the user.

The present invention is directed more 15 particularly to the provision of means for maintaining the rigidity and guiding the mud-hooks in operation. In connection with the mounting of the mud-hooks the invention contemplates the simple operating 20 means, whereby the hooks may be projected to or withdrawn from an operative position, such operating means contemplating the specific details whereby said parts may be readily assembled for use in connection with the 25 usual tractor wheel, or disconnected therefrom when repair or replacement is necessary.

The invention is illustrated in the accompanying drawings, in which:

30 Figure 1 is a view in elevation of the improved wheel.

Fig. 2 is a vertical central section of the same.

35 Fig. 3 is an enlarged detail of the mounting for the mud-hook.

Fig. 4 is a detail of the mud-hook operating means, including the collar and clamp band, the parts being shown separated.

The invention is here shown as applied to 40 an ordinary tractor wheel, embodying a hub 1, having spokes 2 radiating from the ends thereof, and carrying at their outer ends the usual rim 3, having tractor bars 4 secured upon the circumference thereof, all as 45 shown in the drawings. The rim of the wheel is formed at the terminus point with openings 4, of a size and shape corresponding to the sectional contour of the mud-hooks 5. The mud-hooks are here shown as 50 rectangular blocks and inwardly of the rim, such blocks are guided in brackets 6, which brackets are preferably U-shaped members rigidly secured to the inner surface of the

rim and radiating therefrom to guide and support the mud-hooks in operation. The 55 brackets form an essential feature of the present invention, as they rigidly support and guide the mud-hooks.

An operating means is provided whereby the mud-hooks may be projected into an 60 operative position or withdrawn into an inoperative position at the will of the user. This operating mechanism is designed particularly to permit it to be readily secured to the hub of the wheel or to be removed 65 therefrom, and this particular detail forms an essential part of the present invention.

The operating mechanism comprises a collar 7, formed in two sections and adapted to embrace the hub 1. The clamp band 8 is 70 arranged to encircle the collar section, the clamp band being also formed in two parts, having end flanges 9 adapted to abut when the sections of the clamp band are in position to encircle the collar, suitable fastening means 10 engaging the end flanges and securing the clamp band and thereby the 75 collar in fixed relation.

The clamp band is formed at determinate points, corresponding in number to the number of mud-hooks, with transverse recesses 11 on the inner side of the band, in which recesses are fitted the operating rods 12. These rods are U-shaped in form with the cross bars lying in the recesses 11, between 80 the band and collar, the parallel portions of the rods extending outwardly from the collar, as shown. The outer or free end of the 85 rod sections are formed with lateral terminals 13, adapted to seat in openings formed 90 in plates secured to the inner ends of the mud-hooks.

The mud-hooks and operating means or collar and band are thus connected by the rods, and if the band is rotated with respect 95 to the hub, the mud-hooks may be projected beyond the rim of the wheel or withdrawn from such projected position at will.

It is important that means be provided whereby the operating mechanism may be 100 locked in either of its adjusted positions, and such means is here shown as comprising a strip 14 secured to adjacent spokes and formed with a series of openings. An arm 15 is rigidly secured to the collar and projects across and beyond the strip 14. The 105

arm is formed with an opening adapted to register with any one of the openings in the strip 14, and suitable fastening means 16, as a bolt or the like is provided whereby the 5 arm may be secured rigidly to the strip when said arm has been moved to the desired adjusted position.

It is apparent that by adjusting the arm the mud-hooks may be projected into an 10 operative or withdrawn into an inoperative position at the will of the user. It is further evident that in the use of the mud-hooks in projected position, a greater portion of the strain thereon is borne by the 15 brackets, and hence the rods 10 have little or no strain beyond that necessary to project or withdraw the mud-hooks. The operating mechanism here described may be readily assembled with or separated from 20 the hub simply by removing the fastening means of the clamp band, and separating the band and parts of the collar. This provides for readily applying the parts of the operating mechanism as may be necessary or re- 25 moving them for repair or renewal when desired.

Having thus described the invention what is claimed as new is:—

A tractor wheel having mud-hooks operating through the rim thereof, brackets secured on the inner surface of the rim and rigidly supporting and guiding the mud-hooks, a split collar encircling the hub of the wheel, a sectional band clamped about and securing the collar section, said band 30 being formed with transverse depressions on its inner surface, rods comprising U-shaped members having the cross bars seated in the depressions in the band and held against displacement by the clamping of the band 35 on the collar section, the leg portion of the rod loosely engaging the mud-hooks, a strip secured to the wheel spokes, an arm secured to the collar and overlying the strip and means for securing the arm fixedly to the 40 strip in any one of a plurality of adjusted positions, whereby the mud-hooks may be maintained in a projected position or withdrawn, through the turning of the collar 45 in the movement of the arm.

In testimony whereof I affix my signature.

HENRY KURK.
